UNITED STATES PATENT OFFICE.

GEORGE R. SECREST, OF MCRAE, MONTANA, ASSIGNOR OF ONE-HALF TO HUBERT NICHOLLS, OF MCRAE, MONTANA.

CLIMBING FIGURE TOY.

Application filed June 19, 1924. Serial No. 721,079.

To all whom it may concern:

Be it known that I, GEORGE R. SECREST, a citizen of the United States, residing at McRae, in the county of Big Horn and State of Montana, have invented certain new and useful Improvements in Climbing Figure Toys, of which the following is a specification.

The present invention relates to a toy and has for its prime object to provide an amusement device for the young and aims to embody a very simple and efficient construction which will be reliable in operation, very inexpensive to manufacture, durable, strong, and well adapted to the purpose for which it is designed.

The amusement devices aims to simulate a man climbing a pole for the purpose of receiving material and delivering the same to the ground.

With the above and numerous other objects in view as will appear as the description progresses, the invention resides in certain novel features of construction, and in the combination and arrangement of parts as will be hereinafter more fully described and claimed.

In the drawing:

Figure 1 is a side elevation of a toy embodying my invention, portions thereof being shown in section,

Figure 2 is another elevation of the toy taken at right angles to that shown in Figure 1, portions being shown in section,

Figure 3 is an enlarged detail vertical section taken on line 3—3 of Figure 1,

Figure 4 is a detail vertical section taken substantially on the line 4—4 of Figure 2 looking in the direction of the arrows,

Figure 5 is a transverse horizontal section taken substantially on the line 5—5 of Figure 4 looking downwardly, and

Figure 6 is a fragmentary vertical section taken substantially on the line 6—6 of Figure 5 looking in the direction of the arrows.

Referring to the drawing in detail it will be seen that the pole 1 is of hollow construction being provided with the slot 2 which is formed by constructing the pole of sheet metal or the like and bending the same so as to be rectangular in cross section with the meeting ends spaced. A series of teeth openings 3 are arranged alongside of the slot 2 so as to form a rack the purpose of

which is to be hereinafter explained. This pole 1 is fixed to a pan 4 by means of lugs 5 passing through the bottom of the pan and then bent at right angles as is indicated to advantage in Figure 2. A receiving receptacle 6 is adapted to be positioned in the pan 4 for receiving material to be delivered thereto. This receiving receptacle 6 is provided with a handle 6' in order that it may be conveniently lifted from the pan 4 and dumped into a hopper 7 supported on top of pole 1 by brackets 8. This hopper 7 is constructed with a slanting bottom extending downwardly so as to terminate in a spout 9 situated alongside of the upper portion of the pole 1 provided with the slot 2. A valve is associated with the opening at the lower end of the spout 9 and is in the form of a scoop 10 pivoted at 11 to the spout 9 that is adjacent the scoop 10. The closed end of the scoop 10 is provided with an extension 12. It will be readily seen that the normal position of the valve 10 is such that its closed end is lower than its open end thus preventing material from passing through the spout 9. A delivering receptacle 13 is constructed at its closed end with a projection adapted to engage the extension 12 in order to tilt the scoop valve in order that the material such as sand may flow from the hopper 7 through the spout 9, through the scoop valve 10 into the delivering receptacle 13.

A figure 22 is formed to simulate the human body and a plate 15 projects forwardly therefrom to extend through the slot 2. Thus the plate 15 terminates in an eyelet 16 to which one end of a cable 17 is attached. This cable 17 is trained over a pulley 18 rotatable on shaft 19. The other end of the cable 17 has attached thereto a weight 20 sufficient to overcome the weight of the figure 20 and attachments thereto so as to normally retain the same in a raised position. A slot 21 is provided in the forward portion of figure 22 through which a portion of a cog wheel 23 extends. This cog wheel 23 is rotatably mounted on a shaft 24 mounted transversely in the interior of the figure 21. The teeth of this cog wheel mesh with the rack formed by openings 3 so that it will be rotated upon the up and down movement of the figure. A pair of rocker shafts 25 mounted in the figure is arranged in spaced vertical alinement. A pair of cranks 26 are

mounted on each shaft 25 and are connected by a bar 27. The bars 27 are connected by the vertically extending rod 28 which is provided with the projecting lug 29 engageable with the teeth of the cog wheel 23. Arms 30 and legs 31 mounted on the rocker shaft 25 so that they will be oscillated upon rotation of the cog wheel 23 caused by the up and down movement of the figure so as to engage the projecting lug 29 moving the rod 28 back and forth and actuating the crank 26 so as to rock the shaft 25. This motion of the arms and legs simulate the motion of a person's arms and legs when climbing a pole.

10 The receiving receptacle 13 is hinged on the rear of the figure 22 as at 32 that is adjacent the open end of the receptacle so that the closed end thereof will normally be lower than the open end and retained in this position by a stop pin 33 projecting from the figure. A trip arm 34 extends from the pole 1 adjacent its lower end.

15 In considering the operation of this device it will be seen that the hopper 7 is filled with sand or other similar material. The weight 20 will lift the figure so that the projection 14 on the delivery receptacle 13 engages the extension 12 of the scoop valve 10 so as to tilt this scoop valve to the position shown in Figure 3 in order that the sand or like material may flow into the receptacle until sufficient material has been delivered thereto to overcome weight 20 to cause the figure to move downwardly. The figure then moves downwardly and the delivery receptacle 13 is engaged with the trip arm 34 as is indicated in dotted lines in Figure 2 so as to tilt the delivery receptacle and allow the sand or like material to be dumped into the receptacle 6 so that the weight 20 will again overcome the weight of the figure with its attachment and this operation will be repeated until all of the sand from the hopper has become exhausted. During the up and down movement, the rotation of the cog wheel 23 will cause the rocking of the arms and legs of the figure as previously indicated.

20 While the preferred embodiment of my invention has been described in detail, it will be understood that I do not wish to be limited to the particular construction set forth, since various changes in the form, material, and proportions and arrangement of parts, and in the details of construction may be resorted to without departing from the spirit or scope of the invention as hereinafter claimed or destroying any of its advantages.

Having thus described my invention, what I claim as new is:

25 1. A toy of the class described including a hollow pole, a pulley rotatably mounted in the upper end of the pole, a weight

on one end of the cable, a figure movable exterior of the pole and connected with the other end of the cable, a receptacle carried by the figure, said receptacle being pivotally mounted, a hopper positioned on the upper end of the pole and provided with a depending spout having a valve associated therewith, means on the receptacle for engaging the valve to open the same in order that material may flow from the hopper into the receptacle to overcome said weight and to cause said figure to move downwardly, and means at the bottom of the pole for tripping the receptacle to empty the same in order that the weight may again lift the figure all in the manner and for the purpose specified.

30 2. A toy of the class described including a hollow pole, a figure movable up and down the pole, means for normally holding the figure at the upper end of the pole and returning the same to said upper end, a receptacle pivotally mounted on the figure, a hopper positioned at the upper end of the pole and provided with a spout depending therefrom, a scoop valve pivoted adjacent its open end on the spout so as to normally prevent material from passing through the spout, an extension provided on the closed end of the scoop, a receptacle pivotally mounted on the figure and provided with an extension capable of engaging the extension of the scoop valve for tilting said scoop valve and allowing material to flow from the hopper to the receptacle in order to give sufficient weight to the figure in order to overcome the means holding it in a raised position so that said figure will move downwardly, and means at the bottom of the pole for tilting the receptacle to dump the material therein so as to relieve the figure of its weight so that it will return to its raised position.

35 3. A toy of the class described including a hollow pole formed from a sheet of material bent so as to be substantially rectangular in cross section and having its ends slightly spaced to form a slot, projections extending from the lower end of the pole, a pan through which said projections pass for attaching the pole to the pan, said pan forming a base for holding the pole in an upright position, a hopper mounted on the upper end of the pole provided with a depending spout disposed alongside that side of the pole provided with the slot, a scoop valve pivotally mounted on the end of the spout so that its closed end is lower than its open end normally, a pulley mounted in the upper end of the pole, a cable trained over the pulley, a weight on one end of the cable, a figure, a plate extending from the figure through the slot of the pole, said cable attached to said plate whereby the figure is normally held in a raised position on the

5 pole, a receptacle having an open end pivoted adjacent its open end to the figure, a pin extending from the figure for supporting the closed end of the receptacle so that it is normally below the open end thereof, means on the receptacle for engaging the scoop valve to tilt the same to an open position so that material may flow from the hopper to the receptacle overcoming the 10 weight so that the figure may move downwardly, a trip arm extending from the bottom of the pole for engaging the receptacle so as to dump the same of the material which has been delivered therein in order 15 that the figure may move upwardly and means associated with the figure for agitating the arms and legs provided thereon.

4. A toy of the class described including a pole, a figure movable up and down the 20 pole, means for normally retaining the figure

ure at the upper end of the pole, a receptacle pivotally mounted on the back of the figure to simulate a hod-carrier, a hopper positioned at the upper end of the pole and provided with a spout, a scoop bar pivoted 25 adjacent its open end on the spout so as to prevent material from passing through the spout, an extension on the closed end of the scoop, an extension on the receptacle carried by the figure engageable 30 with the scoop extension for tilting the scoop valve and permitting material to flow from the hopper to the receptacle to lower the figure, and a bracket at the bottom of the pole to tilt the receptacle and permit repeated operation of the figure on one filling 35 of the hopper.

In testimony whereof I affix my signature.

GEORGE R. SECREST.
